UNITED STATES PATENT OFFICE.

ABRAHAM OLIPHANT, OF DEERSVILLE, OHIO.

RUNNING-GEAR FOR WAGONS.

SPECIFICATION forming part of Letters Patent No. 242,682, dated June 7, 1881.

Application filed March 17, 1881. (Model.)

To all whom it may concern:

Be it known that I, ABRAHAM OLIPHANT, a citizen of the United States, residing at Deersville, in the county of Harrison and State of Ohio, have invented certain new and useful Improvements in Running-Gear for Wagons; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a side view of my improved draft attachment for vehicles. Fig. 2 is a plan view thereof; and Fig. 3 is a vertical section of the same; and Fig. 4 is a plan, a side view, and a section of the tongue or draft-bar-receiving

20 socket.

This invention relates to improvements in draft or whiffletree attachments for vehicles, having for its object to apply the draft directly upon the front axle, and at the same time to permit the hitching-point to remain at the usual place; and it consists of a U-shaped bent bow, the arms of which may diverge from each other, adapted to permit of the attachment thereto of the whiffletrees, and hung at 25 about its center, with its supporting ring or device connected to a cross-piece of the hound, in close proximity to the axle; and, further, in certain details of construction appertaining to the tongue-socket combined with the hound of 30 the front axle, substantially as hereinafter more fully set forth and claimed.

Referring to the accompanying drawings, A marks the front axle, upon which are supported the rear ends of the hound B, further 35 connected thereto by a bracing bow or frame, B', secured to the under side of the axle.

Bolted upon and to the axle A is the bolster C, moving between guides a fastened to the hound B. A reversed curved bar or brace, b, is fastened to the hound B, with its middle 40 convex surface arranged in close proximity to the axle A.

Between and arranged centrally of the bars B B' of the hound is the tongue or pole socket D, at which point the said bars of the hound 45 are connected or braced to the bar b, and to

the draft-bow, presently described, by rods c c. The socket D is provided upon its upper side with slots d to receive the upper bow or bar, B, of the hound, and upon its under side with 55 similar slots, d', to receive the lower bow or bar, B', of the hound, thus permitting of its being firmly clamped in position. The tongue or pole e is connected to its socket D in the usual way—by pin or otherwise.

60 E is the draftattachment, which consists of a U-shaped bent bow, the arms of which may diverge from each other, as shown in Fig. 2, and are adapted to permit of the attachment thereto of the whiffletrees F, occupying the usual point 65 of hitching the traces or draft-chains. The arms of the draft attachment E are connected and braced together by a cross-bar, f, passing between the rods c above and below it. The convex portion of the bow E is hung at about its middle 70 in a ring, g, connected to the bar b, arranged closely to the front axle, within which it is adapted to slide to yield to unevenness in draft.

75 From the foregoing it will be observed that while the usual hitching-point is preserved the draft is applied directly upon the axle, by which greater leverage is obtained to more readily and with greater power lift a wheel, or both wheels, at the front of the vehicle, where the greatest strain is borne, out of a rut 80 or over an obstruction.

Having thus fully described my invention, I claim and desire to secure by Letters Patent—

1. In a vehicle draft attachment, the U- 85 shaped bow E, hung at its center in close proximity to the front axle, and having its ends provided with suitable clips to hold the whiffletrees in proper position to be hitched to on opposite sides of the tongue, and supported in proper horizontal position by the 90 hounds, substantially as set forth.

2. In a draft attachment for vehicles, the combination, with the frames or bows B B' of the front-axle hound, of the tongue or pole 95 socket D, having upon its upper side slots d and upon its under side slots d', substantially as and for the purpose set forth.

3. The combination, with the axle A, of the front bowed hounds, B B', secured respectively 100 on the upper and under sides of the axle, and arranged parallel with each other, and

the reversed bowed brace or hitching-bar *b*, having its ends secured to the front hounds and its middle convex surface brought in close proximity to the axle, the said hounds and brace being arranged to hold and support the bowed draft-bar *E* and the tongue-socket *D*, substantially as set forth.

In testimony whereof I affix my signature, in presence of two witnesses, on this 1st day of March, 1881.

ABRAHAM OLIPHANT.
